(57) CLAIM

We claim the ornamental design for a golf club putter head incorporating face and rear wall inserts, as shown and described.

DESCRIPTION

FIG. 1 is a perspective view of the face portion of the golf club putter head incorporating face and rear wall inserts.

FIG. 2 is a perspective of the rear wall portion thereof.

FIG. 3 is an elevational of the face portion thereof.

FIG. 4 is an elevational of the rear wall portion thereof.

FIG. 5 is a top plan view of the golf club putter head; and, FIG. 6 is a sectional view, taken substantially in the direction of the arrows 6—6 in FIG. 5.

The broken line showing is for illustrative purposes only and forms no part of the claimed design.
